United States Patent Office.

CHARLES H. STOCKBRIDGE, OF NORTHAMPTON, MASSACHUSETTS, ASSIGNOR TO HIMSELF AND OSMORE O. ROBERTS, OF SAME PLACE.

Letters Patent No. 84,015, dated November 10, 1868.

IMPROVEMENT IN BIT-HOLDER.

The Schedule referred to in these Letters Patent and making part of the same.

To all whom it may concern:

Be it known that I, CHARLES H. STOCKBRIDGE, of Northampton, in the county of Hampshire, and State of Massachusetts, have invented, made, and applied to use, a certain new and useful Improvement in Braces for Bits; and I do hereby declare the following to be a full, clear, and exact description of the said invention, reference being had to the annexed drawing, making part of this specification, wherein—

Figure 1 is a section of the tool-holder at the end of the brace;

Figure 2 is an end view of the same; and

Figure 3, an exterior view of the inner portion of the bit-holder, the screw-sleeve being removed.

Similar marks of reference denote the same parts.

Braces for bits have heretofore been made with a square socket for receiving the polygonal end of the tool, and with a pair of jaws, acted upon by a sleeve having a contracted opening at the end, and screwing over said jaws, to close them around the shank of the bit or tool, as in Letters Patent granted to me, February 19, 1867.

The nature of my present invention consists in a spring applied to the back ends of the clamping-jaws, to open them as the sleeve is screwed forward to release their outer ends from the bit; thereby the said jaws are kept out of the way in entering or withdrawing the bit, and said jaws are also held back in position by the action of said spring.

In the drawing, *a* is a portion of the brace, of any usual or desired construction, within the end of which is the polygonal socket *b*, into which the squared end of the tool is passed, as usual.

A cylinder, *c*, projects beyond the socket *b*, and is formed as part of the brace *a*; and around this cylinder, *c*, a screw-thread is formed, taking a similar thread

on the inside of the screw-sleeve *d*, that is contracted or dome-shaped at its end, terminating with an opening that allows the bit to be entered or withdrawn freely.

I form two incisions into the cylindrical portion *c*, on opposite sides thereof, and extending along at the sides of the socket *b*, in the form of a groove, with a rounded bottom, as seen in fig. 1, and by dotted lines in fig. 2, and into this groove and opening, I place the clamping-jaws *e e*, that are shaped at their forward ends so as to grasp the shank of the tool or bit when the sleeve *d* is screwed down upon them, as in my aforesaid Letters Patent; but I make the inner ends of said jaws *e*, with lips 2 2, and I form a neck around the outside of the socket *b*, at the base of the cylinder *c*, as seen at 3 3, fig. 3, and into this I introduce a contractile spring, *i*, which may be made of India rubber or of metal, in the form of a split ring.

The contraction of this ring, *i*, opens the jaws *e e*, in consequence of the curved form of the bottom of the grooves containing them, so that when pressure against the outer ends of those jaws, *e*, by the sleeve *d*, is released, the said jaws open for admitting or withdrawing the bit or tool, and the ring *i* being in the neck 3, holds the parts properly in place.

What I claim, and desire to secure by Letters Patent, is—

The bit-stock, formed of the clamping-jaws *e*, set in grooves having curved bottoms, in combination with the contractile spring *i* and sleeve *d*, substantially as set forth.

In witness whereof, I have hereunto set my signature, this 24th day of April, 1868.

CHAS. H. STOCKBRIDGE.
